UNITED STATES PATENT OFFICE.

STANISLAW CZAPAS, OF BROCKTON, MASSACHUSETTS.

ESCAPEMENT.

Specification of Letters Patent.

Patented Dec. 9, 1913.

1,080,896.

Application filed January 2, 1913. Serial No. 739,653.

To all whom it may concern:

Be it known that I, STANISLAW CZAPAS, a subject of Nicholas II, Czar of Russia, residing at Brockton, county of Plymouth, Commonwealth of Massachusetts, have invented certain new and useful Improvements in Escapements, of which the following is a specification.

This invention relates to clock escapements, and particularly to the escapement anchor of a pendulum operated clock. In clocks of this class, as at present constructed, the escapement wheel is actuated by an anchor rockingly mounted and connected by an escapement arm with the pendulum. The construction and arrangement of the anchor, relative to the escapement wheel, is such that in its engagement with the escapement wheel there is a noticeable tendency on the part of the anchor to push back on the escapement wheel, thus varying its rotation and impairing the efficiency of the clock as a time keeper.

The present invention was devised to overcome this objection, and to this end I employ a novel form of anchor, the leading end of which is so shaped as to travel past each escapement tooth without pushing it back, and the tail of which is so shaped that when the leading end leaves the escapement tooth said tail will be flat against the tooth which lies next to it.

The construction and principle of my invention will be more fully disclosed in the specification which follows, and in the drawings which form a part thereof, I have shown an illustrative embodiment which I have found well adapted to practical use.

Throughout specification and drawings similar characters of reference will denote corresponding parts, and in these drawings: Figure 1 is a face view of a sufficient portion of a clock escapement to illustrate the application and principle of my invention. Fig. 2 is an exaggerated diagrammatic view of a portion of the escapement wheel and the anchor, illustrating in dotted lines the movement of the anchor relative to the teeth of said wheel. Fig. 3 is a diagrammatic view illustrating the successive positions of the leading end of the anchor in passing a tooth of the escapement wheel.

I have indicated at 1 a portion of a clock plate of the usual type, at 2 the pendulum weight supported from the usual pendulum rod, at 3 the escapement rod bent around

the pendulum rod at one end and connected at its other end to the shank 8 of my improved anchor. Said anchor is rockingly mounted on a pivot pin 4 and is adapted for engagement with the teeth 5 of the escapement wheel 6 mounted on an arbor 7 journaled in the clock plate. The shank 8 of the anchor is formed at its forward end with a downwardly turned leading tooth 9 struck from a radius from the pivot pin 4 and concentric therewith, so that said leading tooth in its engagement with the escapement tooth will ride down along the inner face of the tooth in such a manner as not to reverse or in any way vary the intermittent revolution of said escapement wheel.

The shank 8 is formed at its other end with a substantially straight tail 10 disposed at an obtuse angle to said shank so that a circle having the outer curve of the leading tooth as a portion of its circumference will pass through said tail at its point of juncture with the shank. This tail, furthermore, is set in such a manner as to lie substantially parallel to the leading end of the anchor.

In operation each tooth comes in contact first with the curved end 9 of the anchor indicated in Figs. 2 and 3. Upon the return of the pendulum the end 9 of the anchor is gradually withdrawn, as indicated in Fig. 3, from the tooth until it finally releases the tooth, which then moves past the end of the anchor until the escapement is stopped by a contact of the tooth next in front of it with the tail 10 of the anchor. Upon the recovery of the pendulum, the tail 10 is raised again permitting the partial rotation of the wheel during which partial rotation another tooth 5 moves up to contact with the curved end 9 of the anchor 8. The operation of the device at this point is simply the reversing of the steps shown in Fig. 3, that is to say, beginning at the figure on the right, the tooth 5 reaches the line of swing of the curved end 9 just as that curved end moves down. The result is an initial contact shown in the second figure toward the left and the motion is continued in the third and fourth figures to the left.

Inasmuch as the curved end of the anchor is so shaped that it will travel past the face of each escapement tooth without pushing it back and without varying the intermittent rotation of the escapement wheel, and other things being equal, the clock will keep better

- time than those constructed under existing conditions. This is due to the fact that the curve on the outside of the anchor bend is struck from a radius from the pivot pin of 5 the anchor. This relation of the anchor and tooth in addition to its function of avoiding the backward push has the additional advantage of relieving the shock due to the sudden stopping of the escapement wheel.
- 10 There is in the usual escapement construction a tendency to rebound which is in addition to the backward push of the ordinary anchor. The movement of the curved end 9 as it swings into contact with the corre- 15 spondingly curved face of the tooth avoids the jarring contact and eliminates a part at least of the tendency to recoil.
- When the leading end of the anchor leaves the escapement tooth, the tail will be in a 20 position to intercept the projecting tooth which is moving toward it, as illustrated in dotted lines in Fig. 2. This position enables the leading end of the anchor to take up an-

other tooth of the escapement wheel, thus securing an even, progressive drive of the escapement wheel.

Various modifications in the construction and operation of my device may be resorted to when found necessary, if within the limits of the appended claim.

What I, therefore, claim and desire to secure by Letters Patent is:—

The combination of a toothed escapement wheel and a pivoted anchor, one end of said anchor and one side of said tooth of said wheel being curved on a circle with the pivot of the anchor as a center and the other end of the anchor being on the same curve as is said curved side of the tooth, and interfitting the same in one position of the anchor.

In testimony whereof I affix my signature in presence of two witnesses.

STANISLAW CZAPAS.
